UNITED STATES PATENT OFFICE.

JAMES C. MACFARLANE AND HARRY BURGE, OF CHELMSFORD, ENGLAND, ASSIGNEES
TO THE FIRM OF CROMPTON & COMPANY LIMITED, OF CHELMSFORD, ENGLAND.

DYNAMO-ELECTRIC MACHINE.

1,047,821.

Specification of Letters Patent. Patented Dec. 17, 1912.

Application filed February 17, 1911. Serial No. 609,129.

To all whom it may concern:

Be it known that we, JAMES COLQUHOUN MACFARLANE and HARRY BURGE, subjects of the King of Great Britain, residing at Arc 5 Works, Chelmsford, in the county of Essex, England, have invented certain new and useful Improvements Relating to Dynamo-Electric Machines, of which the following is a specification.

10 This invention has reference to improvements relating to multipolar dynamo electric machines and it has for object an improved construction of dynamo or motor of lighter and more accessible design than 15 hitherto.

Bi-polar dynamo electric machines are known in which the yoke is arranged longitudinally of the armature spindle and forms part of the magnetic circuit of the machine, 20 besides forming supports for the armature bearings, but the distribution of the flux in a multi-polar machine constructed in this manner is entirely different to that in a bi-polar machine, and moreover in a multi- 25 polar machine the pole pieces are capable of being arranged so as to be withdrawn from the machine without disturbing the armature whereas in a bi-polar machine they cannot be so withdrawn.

30 In the herein described multi-polar machine the magnetic circuit from a north to a south pole, both of which are above the armature or both of which are below the armature, takes place as is usual in a plane perpendicular to the armature axis whereas the magnetic circuit from a north pole situated above the armature to a south pole situated below the armature or vice versa takes 35 place in planes parallel to the armature axis and vertical planes perpendicular thereto. A portion of the return flux therefore is carried by a magnetic circuit partly parallel to the armature spindle and partly perpendicular thereto and the iron of which such circuit is composed can therefore be used as a 40 support for the armature bearings.

The appearance of the machine is that of a box having a top, a bottom and two ends, the sides of which have been removed, the 45 poles being removably attached to the top and bottom and the armature being mounted in bearings carried by the ends.

If the pole pieces are mounted in a ring shaped yoke, the plane of such ring instead 50 of being arranged perpendicular to the ar-

mature axis is arranged in the plane of the armature axis and supports the armature bearings.

One constructional form of the invention is illustrated in perspective in the accompanying drawings, the armature shaft being omitted for the sake of clearness.

The field magnets A, A, and B, B, and armature (not shown) are embraced by a frame consisting of a substantially U-shaped pedestal portion C having superimposed thereon and magnetically connected thereto an inverted substantially U-shaped upper portion D, the armature spindle being mounted in bearings carried at E, E, by the sides 60 of said frame which lies in the longitudinal vertical plane of the armature. One pair of pole pieces B, B, is carried upon the pedestal portion C and the other pair A, A, is carried upon the upper inverted U-shaped portion 65 D of the frame, each pole piece being mounted within the frame so as to be capable of removal therefrom laterally of the machine without dismantling any other portion of the machine. The lower pair of pole pieces 70 B, B, may be attached to the pedestal portion C, by means of bolts, not shown, and the upper pair of pole pieces A, A, may be removably secured to the upper portion D of the 75 frame by means of bolts F; the yoke being 80 raised or tilted until the bolts holding the pole pieces B, B, become accessible and can be unscrewed, after which said pole pieces are withdrawn laterally. Normally, the 85 sides of the machine are completely open, but if desired protecting side covers may be 90 detachably mounted upon the frame at each side. By means of such a construction the pole pieces and field coils may easily be 95 withdrawn from the machine for rewinding of the coils or for repairs without removing the armature, and when this is done the armature may be re-wound *in situ* without further dismantling the machine, and the brush gear and commutator are all readily 100 accessible through the open sides of the frame. Further since the frame forms part of the magnetic circuit of the machine, and also forms a support for the armature bearings, the weight efficiency of the machine is 105 increased. Moreover the construction conduces to better ventilation of the armature.

What we claim is:—

In a multi-polar dynamo electric machine, a two-part yoke consisting of a pair of mu- 110

tually opposed vertically arranged U-shaped members connected together detachably and magnetically, a pair of pole pieces mounted within each of said U-shaped members, the connection between said members being out of the line of magnetic flux of the pole pieces, each of said pole pieces being withdrawable laterally outward of the structure without interference with any other part, means to connect said U-shaped members, and means accessible externally of the structure to con-

nect each of said pole pieces with said U-shaped members.

In testimony whereof we have hereunto set our hands in presence of two subscribing ¹⁵ witnesses.

JAMES C. MACFARLANE.
HARRY BURGE.
